UNITED STATES PATENT OFFICE

GEORGE CECIL COOPER, OF LONDON, ENGLAND

COMPOUND ECCENTRIC MECHANISM

Application filed December 21, 1931, Serial No. 582,409, and in Great Britain January 20, 1931.

This invention relates to improvements in compound eccentric mechanism, particularly applicable for use in vibrating a screening or other surface, or for other purposes in which an adjustable variation in a reciprocating motion or travel is of service.

In mechanism employing the variable motion derivable from a compound eccentric, it has been proposed to vary the eccentricity of a pair of eccentrics, mounted one over the other on a revolving shaft, by means whereby the one eccentric may be moved angularly with respect to the other eccentric whilst the shaft is revolving.

The objects of the present invention are to reduce the number of working parts, produce a more compact, reliable, efficient and positive mechanism, reduce the cost of manufacture and generally improve such mechanism.

The present invention comprises a pair of co-axially arranged eccentrics, both of which are splined, keyed or otherwise arranged to rotate with a driving shaft, the one eccentric is fixed to the shaft and the other eccentric is free to be moved axially thereon, an outer eccentric mounted on and free to be rotated on the pair of co-axially arranged inner eccentrics, a strap or its equivalent on the outer eccentric for transmitting the desired motion and means for angularly moving the outer eccentric with respect to the inner pair of eccentrics consisting in the provision of a stud or studs on the one eccentric adapted to be engaged by a helical slot or slots in the other eccentric, and means for axially sliding the axially movable eccentric.

This invention will be now more particularly described making reference to the accompanying drawing in which:

Fig. 1 is a part view in side elevation—partly in section—of one embodiment of this invention.

Fig. 2 is a view in transverse section on line II-II of Fig. 1, and

Fig. 3 is an enlarged diagram showing the centres of shaft and inner eccentric and path of travel of outer eccentric and centres of the latter in two different positions.

Throughout the views similar parts are marked with like letters of reference.

A driving shaft a —the axis of which is designated a^1 —is mounted to be revolved in suitable bearings carried by a frame x . On this shaft a is splined a pair of co-axially arranged eccentrics b , c , the common centre of which is designated b^1 . The one eccentric b is fixed to the driving shaft a so as to rotate therewith in any convenient way, for instance by a key b^2 and set screw b^3 . The other eccentric c is free to slide axially on the shaft a but to rotate therewith, a convenient arrangement being to fix a key a^2 on the shaft to engage a key way c^1 in the bore of the part c . On the pair of inner eccentrics b , c , and free to rotate thereon is mounted an outer eccentric d , the centre of which is designated d^1 rotating round the centre b^1 . A strap e is carried in a bearing on the outer eccentric d and is furnished with a rod e^1 which is connected to the vibrating screen or other mechanism in which an adjustable reciprocating motion or travel is of service. A cap or collar e^2 retains the strap e in position. Angular movement of the outer eccentric d relative to the inner eccentrics b , c , is provided by means of studs or keys d^2 projecting within the bore of the outer eccentric d and adapted to engage helical slots c^2 cut in the surface of the eccentric c . In some cases, the studs might be carried by the eccentric c , in which case the slots c^2 would be cut in the bore of the outer eccentric d . In the diagram, Fig. 3, which shows the amount of variation of travel or range of adjustment possible with the construction shown, a^1 designates the centre of the driving shaft, b^1 the centre of the inner eccentrics b , c , and the path of the outer eccentric d is designated d^3 .

It will be understood that if the pair of inner eccentrics b , c and the outer eccentric d be given the same amount of eccentricity, it is possible, with helical grooves extending 180° round the one part, to secure any required throw of the compound eccentric from nil to maximum.

Any suitable mechanism may be employed

to move the eccentric c axially with respect to the shaft a . In the construction shown, the outer end of the eccentric c is fixed to or made in one with an extension c^3 forming a collar concentric with the shaft a . This collar c^3 is adapted to be engaged by pins f carried by a forked bracket f^1 , the upper end of which is provided with a nut or screwed sleeve f^2 which is engaged by a screw thread g formed on a rotatable shaft g^1 . The forked bracket f^1 is carried by fixed guide rods h carried by brackets h^2 fixed on the frame x and is moved thereon so as to impart axial action to the eccentric c by rotating the shaft g^1 by means of a hand wheel g^2 .

From the above construction, it will be seen that as the mechanism employed to vary the eccentricity of the compound eccentric rotates concentrically with the inner eccentric, the whole gear revolves as a solid unit in any position, all relative motion being avoided between the driving and driven points of contact, which is not possible in previous constructions of mechanism employed in varying the eccentricity of a compound eccentric.

I declare that what I claim and desire to secure by Letters Patent is:—

1. Compound eccentric mechanism comprising a driving shaft, a pair of co-axially arranged eccentrics, both of which are splined to rotate with said shaft, one eccentric being fixed to and the other eccentric being free to move axially on said shaft, an outer eccentric mounted on and free to be rotated on the pair of co-axially arranged inner eccentrics, a strap on the outer eccentric for transmitting the desired motion, and means for angularly moving the outer eccentric with respect to the inner pair of eccentrics.

2. Compound eccentric mechanism comprising a driving shaft, a pair of co-axially arranged eccentrics both of which are splined to rotate with said shaft, one eccentric being fixed to and the other eccentric being free to move axially on said shaft, an outer eccentric mounted on and free to be rotated on the pair of co-axially arranged inner eccentrics, a strap on the outer eccentric for transmitting the desired motion, and means for angularly moving the outer eccentric with respect to the inner pair of eccentrics consisting of a helical slot on the one eccentric, a stud on the other eccentric engaging said helical slot and means for axially sliding the axially movable eccentric of the pair of co-axially arranged eccentrics.

3. Compound eccentric mechanism comprising a driving shaft, a pair of co-axially arranged eccentrics, both of which are splined to rotate with said shaft, one eccentric being fixed to and the other eccentric being free to move axially on said shaft, an

outer eccentric mounted on and free to be rotated on the pair of co-axially arranged inner eccentrics, a strap on the outer eccentric for transmitting the desired motion, and means for angularly moving the outer eccentric with respect to the inner pair of eccentrics consisting of a helical slot on the one eccentric, a stud on the other eccentric engaging said helical slot, and screw mechanism for axially sliding the axially movable eccentric of the pair of co-axially arranged eccentrics.
